DESIGN FOR A COMBINED BAR SERVICE STAND, TRAY, AND BOTTLES

David W. Dunberg, New York, N. Y.

Application February 24, 1940, Serial No. 90,473

Term of patent 7 years

To all whom it may concern:

Be it known that I, David W. Dunberg, a citizen of the United States of America, residing in city of New York, county of New York, and State of New York, have invented a new, original, and ornamental Design for a Combined Bar Service Stand, Tray, and Bottles, of which the following is a specification, reference being had to the accompanying drawing, forming part thereof.

Fig. 1 is a front elevational view of a combined bar service stand, tray, and bottles, showing my new design.

Fig. 2 is a rear elevational view thereof.

Fig. 3 is a side elevational view.

Fig. 4 is a top plan view.

I claim:

The ornamental design for a combined bar service stand, tray, and bottles, substantially as shown.

DAVID W. DUNBERG.
